UNITED STATES PATENT OFFICE.

EDISON M. SMITH, OF WEST HARTFORD, CONNECTICUT.

OIL BURNER.

Application filed March 26, 1924. Serial No. 702,162.

To all whom it may concern:

Be it known that I, EDISON M. SMITH, a resident of West Hartford, county of Hartford, and State of Connecticut, have invented certain new and useful Improvements in Oil Burners, of which the following is a specification.

My invention relates to the class of oil burners more especially adapted for use in furnaces, stoves and other heating appliances, and an object of my invention, among others, is to provide an oil burner that will be simple in construction and particularly efficient in operation.

One form of burner embodying my invention and in the construction and use of which the objects herein set out, as well as others, may be attained, is illustrated in the accompanying drawings, in which—

Figure 1 is a view in central vertical section through an oil burner embodying my invention.

Figure 2 is a view in cross section on a plane denoted by the dotted line 2—2 of Figure 1.

Figure 3 is a view in side elevation of the upper part of my improved burner.

In the accompanying drawings the numeral 5 indicates a base plate, in the form of the device herein shown such plate being located in the bottom of the fire pot of a furnace of ordinary construction. A projection 6 extends downwardly from the plate and has a chamber 7 with which an air inlet 8 communicates.

A rotatable sleeve 9 is mounted in the chamber 7, extending therethrough, this sleeve being supported at its lower end upon bearings 10 in the projection 6 and at its upper end by bearings 11 mounted in a cover 12. These bearings may be of any of the well known types of anti-friction bearings for supporting thrust and radial loads. Air passages 13 extend through the cover 12 and a propeller 14 is secured to the sleeve 9, the blades of the propeller being located opposite the passages 13 so that air forced through the inlet 8 into the chamber 7, being under pressure, will effect rotation of the turbine and consequently of the sleeve 9.

A burner 15 is secured to the turbine and

sleeve to rotate with them, this burner preferably having walls tapering from a lesser diameter to a greater diameter at the top so that oil supplied within the burner will, under the action of centrifugal forces, flow along the walls to the upper edge of said burner. An oil inlet pipe 16 is connected to the lower end of the projection 6 and is extended upwardly to provide an oil supply pipe 17 extending through the sleeve 9 and into the burner 15. Outlets 18 extend radially from the supply pipe and within the burner, these outlets being preferably in the form of short tubes curved downwardly toward the bottom of the chamber in the burner. A cap 19 is secured to a cap adjusting screw 20 screw threaded into the end of the pipe 17 for the purpose of adjusting the size of the burner mouth between the edges of the burner and said cap.

The base plate 5 is spaced from walls 21 of the furnace a distance imposed by conditions and requirements, this space, however, usually not being sufficient to supply an excessive amount of air in addition to that that flows through the passages 13 to the burner and I, therefore, provide means for completing the supply of air, such means being adjustable to regulate the supply. This consists of a damper ring 22 surrounding the cover 12 and resting upon the base 5. This cover 12 is secured to the base and said damper ring is mounted for adjustable rotary movement around the cover, said ring and base being provided with passages 23—24 for air from the lower side of the plate 5 to the upper side thereof.

This construction enables the openings comprising the passages 23—24 to be readily adjustable to such size as to supply just the sufficient amount of air required for combustion purposes to the burner.

The air passing in at the inlet 8 is also made use of in the combustion chamber about the burner, such air flowing through the passages 13 to the turbine and also through ports 25—26, the former being located in the wall of the cover 12 and the latter ports being formed in a damper sleeve 27 surrounding the upwardly projecting part of the cover 12. Said sleeve is rotat-

ably adjustable upon the cover for the purpose of varying the size of the air ports 25 and 26 as may be desired to further regulate the amount of air to be supplied to the 5 burner.

A diffusing plate 28 is mounted on posts 29 extending upwardly from the cover 12, this diffusing plate having perforations 30 for the passage of air from below the plate 10 to the combustion chamber about the burner and above the plate. This plate is of dish-shape with its concave side opening upwardly, and it is adjustably mounted on the posts 29 as by means of adjusting collars 31 fitting 15 the screw threaded upper ends of said posts. This diffusing plate is for the purpose of spreading the air over a comparatively wide area to prevent such air from passing upwardly adjacent to the burner 15 in a concentrated volume.

A space 32 is left between the supply pipe 17 and the sleeve 9 for the purpose of permitting outflow of undesirable accumulation of oil in the burner 15, such oil flowing 25 into a discharge chamber 33 and therefrom through a discharge tube 34 to any suitable place of deposit.

In accordance with the provisions of the 30 patent statutes I have described the principles of operation of my invention, together with the device which I now consider to represent the best embodiment thereof; but I desire to have it understood that the device shown is only illustrative and that the invention may be carried out by other means 35 and applied to uses other than those above set out.

I claim—

1. An oil burner comprising a base with 40 an air inlet chamber therein and an air inlet opening to said chamber, a sleeve rotatably mounted in said chamber, means for rotating said sleeve, a burner connected with said sleeve to be rotated thereby, a fuel supply pipe extending through said sleeve and spaced therefrom to receive excess oil from said burner, and an outlet from said space.

2. An oil burner comprising a base with 50 an air inlet chamber therein and an air inlet opening to said chamber, a stationary cover for said chamber, said cover having air passages communicating with said chamber, a burner located above said cover, air passages extending through said base outside of said chamber, a damper ring rotatably surrounding said cover and having air passages adapted to register with those in the base, means for supplying air to said chamber and therethrough to the burner, and means for 55 supplying fuel to said burner.

3. An oil burner comprising a base with 60 an air inlet chamber therein and an air inlet opening to said chamber, a stationary cover for said chamber, said cover having air passages with ports opening laterally therefrom,

a damper sleeve surrounding said cover and rotatably mounted to control flow of air through said ports, a burner located above said cover, and means for supplying air to said burner.

70

4. An oil burner comprising a base having means to permit passage of air therethrough, a burner located above said base, means for supplying fuel to said burner, and a perforated diffusing plate surrounding 75 said burner underneath its mouth to diffuse air currents flowing therethrough.

5. An oil burner comprising a base having an air inlet chamber with an air inlet opening to said chamber, said base having a 80 laterally extending flange at its upper end with air openings therein, a cover projecting into said chamber and having a flange overlying the flange on the base, a damper ring surrounding the cover and having air openings 85 registering with the air openings in the base, a sleeve rotatably mounted on the base, means for rotating the sleeve, a burner connected with the sleeve to be rotated thereby, and means for supplying fuel to said burner. 90

6. An oil burner comprising a base having an air inlet chamber with an air inlet opening to said chamber, a cover projecting into said chamber and having a shoulder providing a flange resting upon the upper edge of 95 the base, said cover having a projection rising above said flange with lateral openings through said projection, a damper sleeve surrounding said projection to regulate the size of said openings, a sleeve rotatably 100 mounted in said chamber, a burner secured to said sleeve, means for rotating said sleeve and means for supplying fuel to said burner.

7. An oil burner comprising a base having an air inlet chamber with an air inlet opening to said chamber, a cover projecting into said chamber and having a shoulder providing a flange resting upon the upper edge of the base, said cover having a projection rising above said flange with a recess in the 110 upper end of said projection and a series of openings from said recess into said chamber, a propeller mounted within said recess and secured to said sleeve to rotate it, a burner secured to said sleeve, and means for supplying 115 fuel to said burner.

8. An oil burner comprising a base having an air inlet chamber with an air inlet opening to said chamber, a cover projecting into said chamber and having a shoulder providing a flange resting upon the upper edge of the base, said cover having a projection rising above said flange with a recess in the upper end of said projection, a series of 120 openings from the recess into said chamber and a series of lateral openings from said recess, a damper sleeve mounted on said projection to regulate the size of said lateral 125 openings, a burner secured to said sleeve, and means for rotating the burner. 130

9. An oil burner comprising a base with an air inlet chamber therein, an air inlet opening to said chamber, said base having a flange at its upper end with openings there-
5 through, a cover projecting into said chamber and having a flange overlying the flange on the base, a damper ring surrounding the flange on the cover and having openings reg-
istering with those in the flange of the base and rotatable to vary the size of said open-
10 ings, a sleeve, rotatably mounted in the base, a burner secured to said sleeve, and means for supplying fuel to said burner.

EDISON M. SMITH.
